Inv. No. 20:

William S. Kinsley
By Emery Booth Jany. Varney.
Attest.

UNITED STATES PATENT OFFICE.

WILLIAM S. KINSLEY, OF READING, MASSACHUSETTS, ASSIGNOR TO THE RUSSELL COMPANY, OF BOSTON, MASSACHUSETTS, A CORPORATION OF MASSACHUSETTS.

CONVEYER FOR TEXTILE STOCK.

Application filed June 3, 1922. Serial No. 565,783.

To all whom it may concern:

Be it known that I, WILLIAM S. KINSLEY, a citizen of the United States, and a resident of Reading, in the county of Middlesex and State of Massachusetts, have invented an Improvement in Conveyers for Textile Stock, of which the following description, in connection with the accompanying drawings, is a specification, like characters on the drawings representing like parts.

My invention pertains to conveyers for textile stock and has among its objects the provision of simple and inexpensive means for securing the slats of such a conveyer to the links in such manner that the slats may be readily assembled with the chains and may be replaced without disassembling of the chains. My invention, however, will be best understood from the following description when read in light of the accompanying drawings of one specific embodiment of my invention selected for illustrative purposes, while the scope of my invention will be more particularly pointed out in the appended claims.

In the drawings:

Fig. 1 shows a plan of a fragment of a conveyer constructed according to my invention; and

Figs. 2 and 3 are sections on the lines 2—2 and 3—3 of Fig. 1.

Referring to the drawings which show the specific embodiment of my invention selected for illustration, I have provided a pair of parallel sprocket chains, each consisting of a series of links 1 having recesses 3 for the sprocket wheels. In a manner to be described the opposite links carry the ends of slats 4 which provide the surface for carrying the stock moved by the conveyer. As will be understood by those skilled in the art the slats may if necessary be provided with rows of spikes for engaging the stock.

Providing means for attachment of the links to the slats each link is provided with a lateral ear 5 extending toward a link of the opposite chain and each ear is constructed with a flattened under surface 7 and with a tapered upper surface 9, which taper may be in two directions as is illustrated by Figs. 2 and 3, or if desired may have only a taper indicated by Fig. 2.

For securing the slats to the ears I provide the metal bands 13 each of which as indicated in Fig. 3 is shaped to enclose the

ear and the slat, and is provided with an in-turned terminal portion 15 lying against the edge of the ear. The other terminal portion 17 of the band is welded to a portion thereof adjacent the inturned portion 15 as is indicated at 19. It will be understood that the taper above described causes the wedging action either when the ear is driven into the space between the band and slat or when the band is slipped over the slat and is driven over the ear, and that the wedging action causes the slat to be firmly held to the ear.

Each slat is cut away at one end at least, on one side to form a shoulder 21 as indicated in Fig. 1. When the band is placed over the slat, the band abuts the shoulder which serves to hold the band from sliding away from the end of the slat when the tapered ear is driven into the recess between the slat and the band below the inturned portion 15. Preferably, the opposite end of each slat is formed in the same way as just described but if desired for purposes of easy renewal of slats the shoulder 21 may be positioned further toward the center of the slat as is indicated on the lowermost slat at 25 in Fig. 1, in which case the band will be held at the end of the slat by means of a pin 27. In either case, when a worn out or broken slat is replaced one having the shoulder 21 at one end and the shoulder 25 at the opposite end is to be employed. This permits the band being pushed against the shoulder 25 thereby allowing the band to be forced over the adjacent ear after the opposite ear has been driven into the space between the opposite end of the slat and its adjacent band.

Although I have described for purposes of illustration specific embodiments of my invention, it will be understood that I am not to be limited to its particular mechanical details but that wide deviations may be made therefrom without departing from the spirit of my invention.

Claims:

1. In a textile stock conveyer, a pair of sprocket chains, each link of said chains having a lateral ear extending toward the opposite chain, slats extending from each ear to an ear of a link of the opposite chain, and a clamping member for securing the ends of said slats to said ears.
2. In a textile stock conveyer, a pair of

sprocket chains, each link of said chains having a lateral tapered ear extending toward the opposite chain, slats extending from each ear to an ear of a link of the opposite chain, and a clamping member for securing the ends of said slats to said ears.

3. In a textile stock conveyer, a pair of sprocket chains, each link of said chains having a lateral tapered ear extending toward the opposite chain, slats extending from each ear to an ear of a link of the opposite chain, and a band adapted to be forced over each ear and the corresponding end of each slat for clamping the two together.

4. In a textile stock conveyer, a pair of sprocket chains, each link of said chains having a lateral ear extending toward the opposite chain, slats extending from each ear to an ear of a link of the opposite chain, and a clamping member engaging the end of each slat and passing over each ear.

5. In a textile stock conveyer, a pair of sprocket chains, each link of said chains having a lateral tapered ear extending toward the opposite chain, slats extending from each ear to an ear of a link of the opposite chain, and a clamping member engaging the end of each slat and having a recess for receiving an ear and clamping it to said slat.

6. In a textile stock conveyer, a pair of parallelly arranged sprocket chains, slats extending from each link of one chain to a link of the opposite chain, and means for clamping the ends of each slat to the corresponding link.

7. In a textile stock conveyer, a pair of parallelly arranged sprocket chains, slats extending from each link of one chain to a link of the opposite chain, and means for

detachably clamping the ends of each slat to the corresponding link.

8. In a textile stock conveyer, a pair of parallelly arranged sprocket chains, slats extending from each link of one chain to a link of the opposite chain, and clamping means for securing the ends of each slat to the corresponding link constructed to permit the replacement of the slat without disassembly of either chain.

9. In a textile stock conveyer, the combination with a pair of sprocket chains having links with the ears 5, of slats carried by opposite ears, and the slidingly removable bands 13 for clamping the ends of said slats to said ears.

10. In a textile stock conveyer, a pair of sprocket chains having links with laterally extending ears, slats carried by opposite ears, clamping members for securing said slats to said ears, said clamping members engaging the sides of said slats and ears remote from each other and the opposite edges of said ears.

11. In a textile stock conveyer, a pair of sprocket chains having links with laterally extending ears, slats carried by opposite ears, clamping members for securing said slats to said ears, and said slats contacting one side of said ears and said clamping member engaging the other three sides of said ears.

12. In a textile stock conveyer, a pair of sprocket chains having links with laterally extending ears, slats carried by opposite ears, and clamping members slidingly removable by movement lengthwise of said slats for securing said slats to said ears.

In testimony whereof, I have signed by name to this specification.

WILLIAM S. KINSLEY.
